ARMREST

John B. Mazzullo, Washington, D. C.

Application August 20, 1951, Serial No. 16,379

Term of patent 7 years

(Cl. D15—1)

To all whom it may concern:

Be it known that I, John B. Mazzullo, a citizen of the United States, residing at Washington, in the District of Columbia, have invented a new, original, and ornamental Design for an Armrest, of which the following is a specification, reference being had to the accompanying drawing, forming a part thereof, in which

Fig. 1 is a perspective view of an armrest, showing my new design; and

Fig. 2 is a side elevational view of the armrest.

The automobile seat shown in broken lines is for illustrative purposes only.

I claim:

The ornamental design for an armrest, as shown and described.

JOHN B. MAZZULLO.
